UNITED STATES PATENT OFFICE.

LOUIS SANDERS, OF NEW YORK, N. Y.

DESIGN FOR A BELT.

SPECIFICATION forming part of Design No. 33,936, dated January 22, 1901.

Application filed December 1, 1900. Serial No. 38,372. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is a specification, reference being had to the accompanying drawings, forming a part thereof, in which—

Figure 1 represents a plan view of a belt embodying the features of my design, and Fig. 2 is a transverse section taken practically on the line 2 2 of Fig. 1.

The design consists in the enlarged portion at the rear of the belt, having scalloped edges and gradually decreasing in width from the center, and in the facial lines produced on the

said enlarged portion, said lines crossing each other at intervals and losing themselves in the longitudinal edges of the belt, producing serpentine panels and small oval panels at intervals at the longitudinal center. 20

Having thus described my invention, I claim as new and desire to secure by Letters 25 Patent—

The design for a belt as herein shown and described.

In testimony whereof I have signed my name to this specification in the presence of 30 two subscribing witnesses.

LOUIS SANDERS.
